UNITED STATES PATENT OFFICE

LOUIS D. HOULIS, OF DALLAS, TEXAS

GAS PRODUCER

Application filed February 28, 1930. Serial No. 432,052.

This invention relates to new and useful improvements in gas producers.

One object of the invention is to provide improved means of carbureting the fluids, whereby gas is more economically and efficiently produced and an adequate supply is maintained.

A further object of the invention is to produce gas by admixing a raw hydrocarbon liquid with air under pressure and in transit and at the same time cause the air to absorb hydrocarbons or volatile constituents from the conductor through which it is being carried, thus making a more combustible gas.

Another object is to provide an improved gas producer which will be positive in its action, automatic in its operation and simple in construction.

A construction designed to carry out the invention will be hereinafter described together with other features of the invention.

The invention will be more readily understood from a reading of the following specification and by reference to the accompanying drawings in which an example of the invention is shown, and wherein:

Figure 1 is a vertical sectional view of a producer constructed in accordance with the invention,

Figure 2 is a view of the same partly in elevation and partly in section,

Figure 3 is a detail of the air manifold,

Figure 4 is a detail of the carbureting tube, and

Figure 5 is a detail of the automatic gas safety valve.

In the drawings the numeral 10 designates a double walled cylindrical tank having an annular water jacket 11 and a carbureting chamber or reservoir 12. A movable bell 13 telescopes into the jacket and has its lower end immersed, whereby a water seal is had and the usual gasometer is produced.

The tank may be partially embedded in the ground or otherwise mounted. An arched frame 14 is mounted on the tank and the bell 13 rises and falls within this frame. A flexible connection 15 having one end attached to the bell passes over pulleys 16 on the frame and carries a pendant weight 17 on its oppo-

site end. The weight may be regulated so as to compensate the gas pressure within the gasometer in the usual manner.

Within the chamber 12 is mounted a carburetor 18 which includes a spool 19 mounted in the upper portion of the chamber on an annular ring 20 secured to the inner wall of said chamber. The spool has legs 21 resting on said ring and is also provided with a central vertical column or flue 22.

A flexible tube 23 is coiled in horizontal layers around the column on the spool, said layers being alternately wound inward and outward or otherwise, so as to give a long tortuous passage. The tube is continuous from one end to the other and while made of absorbent material, such as fabric, it is impervious to air. As is shown in Figure 4, the tube has a helical wire liner 24 which not only holds the tube in shape and prevents flattening, but causes the fluids passing through the tube to whirl and thus lengthen their travel.

A compressed air supply pipe 25 enters the bottom of the tank and extends vertically through the chamber 12 and column 22. The pipe is connected to a nozzle 26 at its upper end and the nozzle is inserted in one end of the tube 23. A fuel supply pipe 27 extending into the tank contiguously to the air pipe has its upper end terminating in the nozzle 26. A gas riser 28 extends down through the column and the chamber and is connected to a gas discharge pipe 29. A fuel drain pipe 30 also leads from the bottom of the chamber 12.

A quantity of hydrocarbon oil such as gasoline is stored in the chamber 12 below the carburetor. The drain pipe 30 connects with a fuel pump 31 and forms an intake therefor, while the fuel supply pipe 27 also connects with said pump. The air pipe 25 connects with an air pump 32 and both pumps are driven by an electric motor 33.

An air manifold 34 connects with the air pump 32. The manifold is T-shaped having one leg connected to the pump. In its upright leg it has a butterfly valve 35 provided with a lever 36 and an indicating quadrant 37; while in its horizontal leg it has a butterfly valve 38 provided with a lever 39 and an indicating quadrant 40. In the upright leg

above the valve 35 is a downwardly opening check valve 41 for admitting air, but preventing the escape of fluids from the manifold.

The pump 32 draws in air from the manifold 34 and delivers it to the pipe 25 under pressure and this pipe discharges it through the nozzle 26 into the tube 23. The pump 31 sets up a circulation of fuel liquid from the chamber 12 through the pipe 30 and discharges said liquid into the pipe 27 which conducts it to the nozzle 26.

Air and fuel liquid are thus forced into the upper end of the coiled tube 23. As this raw fuel flows down through the tube the latter is saturated and the air is thus caused to absorb volatile constituents or hydrocarbons as it passes along the wet inner walls of said tube. The air is also admixed with the raw liquid and thereby a most efficient carburation takes place. The long travel induced by the helical liner 24 assures the discharge of a highly combustible gas from the lower end of the tube.

The emitted gas flows out under the spool 18 and passes upward through the column 22 and along the outside of the spool. By contact with the outer convolutions of the tube still further hydrocarbons are absorbed. The gas collects in the bell 13 and is compressed therein due to the downward pressure of the bell and the pressure built up by the pumps. The liquid fuel which escapes from the tube falls into the chamber 12 is again circulated by the pump 31. The gas compressed in the bell 13 is thus placed under pressure and escapes through the riser 28 and pipe 29 from which it is supplied to service.

The manifold 34 is connected in the pipe 29 and normally the valve 38 is closed, but by opening said valve and partially or wholly closing the valve 35 the gas from the pipe 29 is wholly or partially recirculated and again carbureted by the pump 32 and carburetor 18.

The motor 33 drives the pumps and when the gasometer becomes full of gas and the bell rises to its limit, it is desirable to stop the gas producing operation. An electric switch 42 is connected in the electric circuit A—B of the motor. This switch has an arm 43 pivoted to a stud 44 on a vertical shifting link 45. The link is pivoted at its ends to the outer ends of levers 46 which are pivoted on the frame 14.

The inner ends of the levers project into the path of a finger 47 on the top of the bell. When the bell falls to its lower limit because of the depletion of gas the finger engages the lower lever 46 and swings it to the position shown in Figure 1, whereby the link 45 is moved upwardly and the switch arm 43 is likewise swung to close the switch. This starts the motor 33 and the pumps 31 and 32, thus putting the producer in operation.

Should the electric power fail or for any reason the lever 46 or switch 42 fail to oper-

ate when the bell falls, I provide a safety cutoff valve 48 (Figure 5) in the gas pipe 29. This valve has an arm 49 connected to the bottom of a link 50 which has its upper end pivoted to a tripping lever 51. The lever is pivoted at 52 and has a depending lug 54 engaging the upper end of a coiled spring 55 resting on a support 56. The spring is under compression so that when the lever is swung and the lug thrown out of line, said spring will expand, thus further actuating the lever and holding it in the position to which it is swung.

The lever is provided with a hinged dog 57 which projects into the path of the finger 47. When the finger passes below the lever 46 and the producing elements fail, said finger will engage the dog 57 and swing the lever 51, whereby the valve 48 will be closed. The finger 47 will probably pass below the dog by riding off of the end of the latter so that when the bell is again charged and the lever 51 swung back to its normal position, said finger will trip past the hinged dog upon the upward movement of the bell.

Various changes in the size and shape of the different parts, as well as modifications and alterations, may be made within the scope of the appended claims.

What I claim, is:

1. In a gas producer, a gasometer, a carburetor in the gasometer, means for supplying air and hydrocarbon liquid to the carburetor, the carburetor including an absorbent tortuous conductor into which the air and liquid are discharged, whereby the air and liquid are mixed, also whereby the air absorbs hydrocarbons from the conductor, means for conducting gas from the gasometer, and means for recirculating the discharged gas through the conductor.

2. In a gas producer, a gasometer including a bell, a carburetor within the gasometer, means for supplying air and hydrocarbon liquid to the carburetor, a gas pipe extending from the carburetor and gasometer, a normally open safety valve in the gas pipe, means for operating the valve to close it, and means on the bell of the gasometer for actuating said valve closing means when said bell reaches its lowermost position.

3. In a gas producer, a gasometer, a carburetor in the gasometer including an absorbent conductor, a chamber in the gasometer below the carburetor for containing liquid fuel, and a pump connected with the chamber and also connected with the conductor for circulating the fuel liquid thereof.

4. As a sub-combination in a gas producer, a carbureting spool comprising a central column and a continuous absorbent tube coiled about the column in superposed layers, and each layer including a plurality of convolutions of said tube, whereby an elongated tortuous passage is provided.

5. In a gas producer, a double walled tank having a water jacket including a fuel chamber, a gasometer bell telescoping into the jacket, a carbureting spool stationary within the upper end of the chamber, the lower portion of the chamber containing liquid fuel, the carburetor including a coiled absorbent tube having its entrance at the upper end of the carburetor and its discharge at the lower end, an air pipe extending to the carburetor and connected with the tube, an air pump connected with the air pipe, a fuel pump connected with the chamber, a fuel supply pipe leading from the fuel pump and connected with the intake end of the tube, a gas discharge pipe leading from the carburetor, and a bypass extending from the gas discharge pipe to the air pump.

6. The combination set forth in claim 5, with means for regulating and controlling the supply of air and gas to the air pump.

In testimony whereof I affix my signature.

LOUIS D. HOULIS.
